UNITED STATES PATENT OFFICE.

ORVAL R. PLATTER AND JASPER T. BALL, OF NORTH VERNON, INDIANA.

SOUND AMPLIFIER.

Application filed March 30, 1927. Serial No. 179,619.

Our invention relates to horns or sound amplifiers to be used with phonographs, wireless receiving sets, and the like, and it is an object of the invention to provide a device of this character which will segregate and amplify the tone waves of the human voice and musical instruments and will emit such tone waves in a manner whereby they may be clearly and distinctly heard and with pronounced modification of static and inharmonious sounds.

5 Referring to the accompanying drawings which are made a part hereof and on which similar reference characters indicate similar parts,

10 Figure 1 is a part sectional and part elevational view of one application of our invention,

15 Figure 2, a front elevation,

20 Figure 3, a top plan view,

25 Figure 4, a section on the line 4—4 of Fig. 2.

In the drawings reference character 10 indicates a sound box, 11 a flared outlet or bell-mouth, and 12 a sound receiving and conveying tube or neck of tortuous shape and of constantly increasing diameter from end to end.

The sound box 10 is preferably formed of 30 ply-wood or laminated wood structure and has its sides preferably formed integrally with the sides of the flared bell 11. The ends of the sound box are disposed in substantially parallel relation, and upon the 35 inside of one of said ends is mounted a pyramid or cone-shaped resonator 13. The opposite end of the sound box is provided with an opening in which is disposed the large end of the tube 12 which conducts 40 the sounds waves from a loud speaker unit or the like into the sound box.

The sound receiving and conveying tube 12 is formed of plastic resonant fibrous material and has its large end formed in communication with one end of the sound box from which it extends perpendicularly for a short distance and is doubled upon itself and extends along the side of the flared bell-mouth 11 and is redoubled upon itself at 45 the opposite end of the side. The side of the bell-mouth 11 is provided with a curved tapered depression 14 in which the tube 12 is disposed thus providing a very compact arrangement. The small end of the tube or neck is disposed at the opposite end of the sound box on the exterior of the same for

attachment to a loud speaker unit or the like and the taper of said tube is of a general character which insures most satisfactory results.

60 The sound box 10 is preferably provided with an extension 15 which forms in conjunction with the lower flared outlet 11 a support for the device by means of which the extremity of the outlet 11 may be supported in upright position.

An arcuate partition member 16 is disposed within the upper portion of the sound box and such partition member 16 is disposed edgewise across the end of the tube 12 and provides a substantially crescent-shaped opening 17 into the upper portion of the sound box and a larger substantially circular opening in the lower portion of the sound box from which sound is emitted. A 70 partition plate 18 of ply-wood or laminated wood structure is disposed transversely within the bell-mouth 11 substantially at right angles to and in engagement with the arcuate partition member 16 for dividing the bell-mouth 11 into two compartments for dividing and segregating a portion of the sounds propagated through the tube 12.

The tube 12 is provided on its interior with a narrow rib 19 comprising a strip of wood 80 or the like material which extends continuously therethrough and serves the double purpose of strengthening the sound receiving and conveying tube 12 and dividing the tones. This rib serves to secure the full 85 tonal scale and to bring in the booming base notes and is assisted in its function of the reflection of tone and multiplication of the frequency of the tone waves by a plurality of semi-circular ribs 20 disposed in spaced 90 relation within the upper portion of the tube 12. This combination of ribs reflects the 95 tone waves in two directions as will be obvious and gives a harmonious or uniform circular motion which results in the segregation 100 of speech distinctly and naturally as well as musical instruments and the like which are classified and separated and are rendered recognizable when played in orchestras and the like.

105 The tube 12 is provided with a plurality of slots 21 adjacent its small end about which slots is disposed a rubber ball 22 such construction being designed to reduce vibration and to modify static as well as to prevent 110 to some extent cramping or distorting of tones.

In actual experience it has been found that with our device one very disagreeable form of static, which is of an intermediate nature and comes in with a loud jarring sound and then fades away to return again in a few minutes, is muffled to a large extent and practically eliminated and that part which is not eliminated is made more of a tone than a noise.

16 It will be obvious to those skilled in the art that various changes may be made in our device without departing from the spirit of our invention, and we, therefore, do not limit ourselves to what is shown in the drawings and described in the specification, but only as set forth in the appended claims.

Having thus fully described our said invention, what we claim as new and desire to secure by Letters Patent, is:

20 1. A horn or sound amplifier comprising a sound box, a flared bell at one side of said sound box, a sound receiving tube extending outwardly from another side of the sound box around the same and terminating at the 25 opposite side thereof, the intermediate portion of said tube being disposed in a depression in the side of said bell, substantially as set forth.

2. A sound amplifier comprising a sound 30 box having a truncated member extending from one side of the same, a tubular sound receiving element of increasing cross sectional area having its large end connected to said sound box and its intermediate portion 35 disposed in a recess formed in one side of said truncated member, and a supporting element at the bottom of said sound box forming with the lower extremity of the truncated member a means for supporting the amplifier, substantially as set forth.

3. A sound amplifier comprising a sound 40 box having a truncated member extending from one side of the same, a tubular sound receiving element of increasing cross sectional area having its large end connected to said sound box and its intermediate portion 45 disposed in a recess formed in one side of said truncated member, a supporting element at the bottom of said sound box forming 50 with the lower extremity of the truncated member a means for supporting the amplifier, and a narrow rib disposed longitudinally within said tubular sound receiving element, substantially as set forth.

55 4. A sound amplifier comprising a sound box having a truncated member extending from one side of the same, a tubular sound receiving element of increasing cross sectional area having its large end connected to 60 said sound box and its intermediate portion disposed in a recess formed in one side of said truncated member, a supporting element at the bottom of said sound box forming 65 with the lower extremity of the truncated member a means for supporting the

amplifier, and a plurality of transverse ribs disposed within said tubular sound receiving element, substantially as set forth.

5. A sound amplifier comprising a sound box having a truncated member extending 70 from one side of the same, a tubular sound receiving element of increasing cross sectional area having its large end connected to said sound box and its intermediate portion 75 disposed in a recess formed in one side of said truncated member, a supporting element at the bottom of said sound box forming with the lower extremity of the truncated member a means for supporting the amplifier, a narrow rib disposed longitudinally within said tubular sound receiving element, and a plurality of transverse ribs 80 disposed within said tubular sound receiving element, substantially as set forth.

6. A sound amplifier comprising a hollow 85 structure having a substantially rectangular portion and a flared mouth extending therefrom, a sound receiving tube of increasing diameter having its large end communicating with said sound box adjacent one 90 side of the flared mouth, said receiving tube being formed of plastic material and extending about said flared mouth and resting in a depression in the side of the same, substantially as set forth.

7. A sound amplifier comprising a hollow structure having a substantially rectangular portion and a flared mouth extending therefrom, a sound receiving tube of increasing 100 diameter having its large end communicating with said sound box adjacent one side of the flared mouth, said receiving tube being formed of plastic material and extending about said flared mouth and resting in a depression in the side of the same, and a resonator formed of a pyramid disposed in the sound box at the side opposite its connection with the receiving tube, substantially as set forth.

8. A horn comprising a diverging end provided with an amplifying chamber at its small end, a sound conveying tube connected to said amplifying chamber at one side of the same and winding about said diverging end and disposed within a depression in the outer side of the same, and a pyramid-shaped 110 resonating reflector within the amplifying chamber, substantially as set forth.

9. A horn comprising a diverging end provided with an amplifying chamber at its 120 small end, a sound conveying tube connected to said amplifying chamber at one side of the same and winding about said diverging end and disposed within a depression in the outer side of the same, a pyramid-shaped 125 resonating reflector within the amplifying chamber, a partition member disposed in said diverging end, and a second partition member engaging the edge of the first-mentioned partition member and extending into 130

said sound conveying tube for dividing the sounds emitted, substantially as set forth.

10. A horn comprising a diverging end provided with an amplifying chamber at its small end, a sound conveying tube connected to said amplifying chamber at one side of the same and winding about said diverging end and disposed within a depression in the outer side of the same, a pyramid-shaped 10 resonating reflector within the amplifying chamber, a partition member disposed edge-wise across the inner end of said sound con-

veying tube and a second partition member dividing said diverging end into two compartments and snugly fitting against the 15 first-mentioned partition member, substantially as set forth.

In witness whereof, we have hereunto set our hands at North Vernon, Indiana, this 26th day of March, A. D. nineteen hundred 20 and twenty-seven.

ORVAL R. PLATTER.
JASPER T. BALL.
